UNITED STATES PATENT OFFICE.

HORACE L. ROBERTS, OF BROOKLYN, NEW YORK.

TAPE-FASTENER.

1,205,024.

Specification of Letters Patent. Patented Nov. 14, 1916.

Application filed February 11, 1916. Serial No. 77,570.

To all whom it may concern:

Be it known that I, HORACE L. ROBERTS, a citizen of the United States, and a resident of Brooklyn, in the county of Kings and 5 State of New York, have invented certain new and useful Improvements in Tape-Fasteners, of which the following is a specification.

This invention relates to a tape fastener 10 of simple construction which is adapted to securely connect the ends of tapes, such as for example, are used in printing presses, folding machines and similar devices. The fastener may be readily fitted to the tape 15 and forms between the connected tape ends a hinge joint of great strength and compactness.

In the accompanying drawing: Figure 1 is a plan of a fastener embodying my invention showing it applied to the tape; Fig. 2, a section on line 2—2 Fig. 1; Fig. 3, a cross section of the fastener showing it partly bent; Fig. 4, a plan of the fastener before being bent; Fig. 5, a cross section on 25 line 5—5 Fig. 4; Fig. 6, a cross section on line 6—6 Fig. 4, and Fig. 7, a perspective view of the coupling member.

The device consists essentially of two oblong clips or bendable sheet metal plates 1, 30 the length of the clips corresponding substantially to the width of the tapes 2 to be connected. Each clip 1 is adapted to be bent along its longitudinal axis, so as to form a pair of wings that straddle the end 35 of the tape. These wings may be secured to the tape by means of a plurality of integral teeth 3, which are punched out of the plate, and are arranged near the edges of the latter. Across the axis of plate 1, extend a 40 plurality of transverse slots 4, four of such slots being shown, though their number may be readily varied, a single slot being in fact, sufficient for a fastener of small size. Each slot 4, is intersected at its center by a longitudinal groove or depression 5, formed in the face of plate 1 and extending along the axis thereof, the groove being rounded in cross section, to correspond somewhat to the knuckle of a hinge joint.

50 The two plates constructed as described, which should be alike in all respects, are

adapted to be hingedly connected to each other by means of coupling members one of which is more fully illustrated in Fig. 7. This coupling member consists essentially 55 of two parallel pins 6, which are of circular shape in cross section, and are connected to each other at their center by a flat or other web 7, the whole approximating the letter H in appearance. 60

In use, the two pins 6 of the coupling member are passed through the corresponding slots 4 of a pair of superposed clips 1, (see upper slot Fig. 4), the coupling members are given a quarter turn to become seated with their pins in the grooves 5 so as to lock the plates together (see lower slots Fig. 4), the clips are bent on their longitudinal axes (Fig. 3), until brought into engagement with the ends of a tape, or tapes 70 2 which have been introduced into the clips, and then the teeth 3 are upset to effect a tight hold of the clips on the tapes.

It will be seen that the fastener constructed as described, is of great simplicity, may 75 be readily assembled and applied, and permits a free rocking motion of the pins within their sockets, so that a hinge motion between the two members of the fastener may freely take place. 80

When the tape turns over small rollers, the clips will swing so freely at their hinge-connection, that the teeth on such clips are relieved from excessive strain. Finally, ample metal is provided for in the clip plates 85 at the hinges, so that the latter is thoroughly stiffened and not liable to open.

I claim:

A tape fastener comprising a pair of oblong bendable plates having slots extending 90 transversely of the same, said plates being provided with grooves arranged axially thereto and intercepted by said slots, an H shaped coupling member composed of a pair of parallel pins and of a web connecting 95 said pins, said pins being adapted to lie in said grooves and the webs to project through said slots, whereby said plates are locked together, said plates provided with means for securing them to a tape.

HORACE L. ROBERTS.
